UNITED STATES PATENT OFFICE.

WILLIAM B. COATES, OF PHILADELPHIA, PENNSYLVANIA.

IMPROVEMENT IN CONVERTIBLE LOUNGES.

Specification forming part of Letters Patent No. 153,665, dated August 4, 1874; application filed April 11, 1874.

To all whom it may concern:

Be it known that I, WM. BAILY COATES, of the city and county of Philadelphia, and State of Pennsylvania, have invented a new and useful Improvement in Convertible Lounges; and I do hereby declare the following to be a clear and exact description of the nature thereof, sufficient to enable others skilled in the art to which my invention appertains to fully understand, make, and use the same, reference being had to the accompanying drawings, making part of this specification, in which—

Figure 1 is a side elevation of the device embodying my invention. Fig. 2 is a bottom view thereof. Fig. 3 is a view of the under side of the head-leaf. Fig. 4 is a view of the under side of the foot-leaf. Fig. 5 is an end view of Fig. 1. Figs. 6 and 7 are views showing the lounge variously converted.

Similar letters of reference indicate corresponding parts in the several figures.

This invention consists in the construction of a lounge and various appurtenances thereto, which may be folded and combined in compact form, and adapted to be converted into several articles of household use.

Referring to the drawings, A represents the main or center frame, which is supported upon hinged legs B, adapted to be folded against the under side of the said frame A. The legs B are hinged to brackets B', which are secured to the under side of the center frame A. Such bracket consists of a horizontal plate, B'', from which project vertical arms B''', one of which is larger than the other, and to which a leg, B, is hinged. A shoulder, b', is formed on the leg, and when the leg is folded its hinged end moves in the channel between the arms B''', the shoulder b' coming over the short arm B'''. A rib or ribs may be applied to the long arm, and it will be seen that the plates B'' connect and secure the corners of the center frame. The leg is firmly jointed and braced, lateral play thereof is prevented, and the strength of the arm B''' is increased. C represents the foot frame or leaf, which is hinged to one end of the frame A, and D represents the head-leaf, which is hinged to the other end of the frame, and folds over and on the frame C. The head-leaf D will be attached

to the center frame A by a hinge, a', that is wider or broader than the hinge a, which connects the foot-leaf C and center frame. One leaf or butt of each hinge will be set out or shouldered, so that the two leaves or butts of a hinge may be secured to the sides of the respective parts without cutting away and weakening said parts, and thus permitting said parts to be of uniform widths. By this construction, also, the center frame may be formed the same at both ends, and when the parts are unfolded, as in Fig. 7, the head-leaf, center frame, and foot-leaf will be level, or continuous of each other, in the same right line. On the head-leaf D is placed a removably-connected seat-frame, G, whose under side has at one end a hook or catch, which enters a horizontal socket or slot formed in the head-leaf D, and at the other end a pin which enters an opening in the said leaf at the end or side opposite to the slot, the hook and pin being shown at b b, Fig. 1, and the socket and opening at c c, Fig. 3. Fig. 3 represents the under side of the head-leaf D, which will face uppermost when the seat-frame G is removed. When the seat-frame G and the leaves C D are in folded position, (shown in Fig. 1,) hooks or catches d d, respectively on the ends of the frame G and leaf C, engaging with the pins e e on the end of the leaf D, serve to connect the main frame A, leaves D C, and seat-frame G, and hold them in compact form, as seen in Figs. 1 and 5. H, Figs. 3 and 7, represents double or extensible legs, which consist of two legs hinged to and folding within the head-leaf D, the two parts or legs, when partially opened, being adapted to support the leaf D in a horizontal position, and when entirely swung out or opened, to support said leaf in an inclined position, both positions being shown at the right side of Fig. 7. Braces J and pins K are provided for keeping the legs properly extended. When the legs and braces are folded within the leaf D, they are held there by the buttons or catch f, suitably applied. When the legs H are folded the pins or bolts K are not required for use, in which case they will be inserted into openings in the leaf D and held there by elastic loops f', stretched from pins g, or by other appliances. (See Fig. 3.) L, in Fig. 3, represents straps, which are folded

within the leaf D and pass through loops M, secured to opposite sides of the leaf D, and its ends are slipped over hooks N, projecting from one end of the leaf D. Thus the straps are in compact form, and securely and nicely located when not in use, as seen in Fig. 3. P, Fig. 3, represents hooked plates, which are hinged to the leaf D, and arranged over depressions p' at opposite sides of the outer end of said leaf D, and adapted to have the straps L, which are connected at one end of the leaf, pass through or around the same for supporting the head-leaf in an elevated position, as seen by the dotted lines, the parts being marked D P L, Fig. 7. Legs Q and braces R are hinged to the foot-leaf C (see Fig. 4,) and said legs may be single or double, and, in either case, the legs and braces will fold in the leaf C, as shown in Fig. 4, and support said leaf, as shown at the left side of Fig. 7. A socket and opening, c, similar to those formed in the head-leaf may be formed in the foot-leaf, so that when the head-leaf is unfolded and elevated, the seat-frame G may be applied to the unfolded foot-leaf, and form a seat proper, the back of which will be the elevated head-leaf. S represents a foot-board, which is adapted to be applied to the ends of the outer end of the foot-leaf C, (see left side of Fig. 7,) and, when not in service or use, to be placed within the leaf C, where it is held by its pins h entering openings in said leaf, and elastic straps h' being connected to the leaf and embracing the sides of the board. On the under side of the main or center frame A, as shown in Fig. 2, there will be provided a series of pockets or fastenings, m, for various appurtenances, as follows: A rolled band, T, stretcher-rod U, having a clamping-screw, V, a spread-brace and side guard, W, and head-board X. Hooks Y are secured to opposite sides of the main frame for attachment to the end of the straps L, when the head-rest is elevated, as seen in Fig. 7. The screws Z, which serve to hold the legs B, when unfolded, (see Fig. 5,) may be applied to or stored on the frame C when the legs are folded or closed. (See Fig. 2.) The spread-brace and side guards W consist of two rods or bars, hinged to each other at one end, and one of the rods is extended beyond the axis of the two rods to form a curved or angular end, p, which is designed to enter a slot, q, on the upper face of the center frame A and lock therewith. The free ends of the rods are turned or bent laterally in opposite directions to form hooks s, which will enter openings t, formed in the upper faces of leaves C D. (See Fig. 6.)

In Fig. 1 there is shown an elevated ottoman or stool, the seat-frame G constituting the top thereof, and covering the under side or back of the head-leaf D with its several fixtures. By folding the legs B there will be formed a low-down ottoman or stool.

In order to impart a nice finish to the device, and also to conceal the various appurtenances on the under side of the center frame, fringe

or trimming may be attached to the sides of the center frame, as shown in the dotted lines in Fig. 1.

By unfolding the head and foot leaves, and properly operating the legs H Q, (referring to Fig. 7,) the leaves and center frame will be horizontally continuous of each other and form a bed. One of the leaves may be elevated so that a lounge is produced. One of the leaves may be elevated and the other lowered to constitute an invalid-chair. The leaf that is elevated may be supported to a certain height by the legs H, and to a greater height by the extension of the legs H.

The straps L, as has been stated, may be employed to support the head-leaf, openings or eyes in the straps fitting on the hooks Y, determining the angle of the said leaf. The straps thus become side guards or arm-straps for the chair, which is produced by throwing up the head-leaf and applying the seat-frame G to the foot-leaf, which remains unfolded on the center frame A.

The various leaves and frames may be upholstered, as desirable, and cushions are adapted to be applied to the converted parts in any well-known manner.

The two leaves may be thrown up and held in a vertical position by the face and guard W, as shown in Fig. 6. The band or guard T is then run around the leaves, whereby there is formed a child's crib, or, if the device is turned on side, an inclosure for children.

By applying rockers, the device may be converted into a rocking cradle.

The foot-leaf C may be unfolded to a horizontal position, and the stretcher-rod U clamped thereto. One end of the band may then be connected to the head-leaf and the other end to the stretcher-rod U, as shown by dotted lines a'', Fig. 6, whereby there is formed an extended crib. In this case one of the rods of the brace and guard W will be hooked over the band.

The head and foot boards S X may be applied to various converted parts.

Numerous changes or conversions may be made in the lounge, it being only necessary to unfold certain parts, arrange others, and locate the appurtenances, all of which will suggest themselves to those concerned. The various conversions may be made for high or low purposes by respectively folding or unfolding the legs B.

Having thus described my invention, what I claim as new, and desire to secure by Letters Patent, is—

1. In a convertible lounge having the head-leaf D, foot-leaf C, and center frame A, arranged as described, the detachable seat-frame G, adapted to be applied to either the head-leaf, foot-leaf, or center frame, substantially as set forth.

2. The legs B, in combination with the brackets B', consisting of plates B'' and arms B''', constructed and operating substantially as set forth.

3. The detachable seat-frame G, provided with hook and pin *b b*, and the head-leaf D, provided with socket and opening *c c* on its lower side, combined and operating substantially as and for the purpose set forth.

4. The seat-frame G, in combination with the head and foot leaves, the catches *d d* and pins *e e*, and the center frame A, substantially as and for the purpose set forth.

5. The combination, with the head-leaf D, of the extensible legs H and braces J, substantially as and for the purpose set forth.

6. The straps L, in combination with the hooks N and loops M of the leaf D, substantially as and for the purpose set forth.

7. The combination, with the strap L, of the hook-plates P, hinged to the leaf D, and arranged over the depression *p* of said leaf, substantially as and for the purpose set forth.

8. The spread-brace and side guard W, in combination with the head and foot leaves C D and the center frame A, substantially as and for the purpose set forth.

9. The spread-brace and side guard W, consisting of two rods hinged to each other, one of which is extended beyond the axis at *p*, and the free ends are hooks, as at *s*, substantially as and for the purpose set forth.

10. The brace and guard W, band T, and stretcher U, in combination with the head-leaf D, foot-leaf C, and center frame A, substantially as and for the purpose set forth.
